(57) **CLAIM**

The ornamental design for a jogging belt, as shown and described.

DESCRIPTION

FIG. 1 is a perspective view of a jogging belt showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view taken along line 8-8 of FIG. 6 thereof;

FIG. 9 is a cross-sectional view taken along line 9-9 of FIG. 6 thereof;

FIG. 10 is a bottom perspective view thereof; and,

FIG. 11 is perspective view of the jogging belt shown in use. The portion of the jogging belt shown in broken lines depicts environment and is shown for illustrative purposes and forms no part of the claimed design. The jogging belt is shown with symbolic breaks in its length. The appearance of any portion of the article between the break lines forms no part of the claimed design.

The dash dot lines shown in FIGS. 1 and 10 represent a boundary line.
